ELLIPSOGRAPH

Rapolas Aukstuolis, Stamford, Conn.

Application May 12, 1952, Serial No. 287,373

1 Claim. (Cl. 33—27)

1

This invention relates generally to the field of drafting instruments and more particularly to improved forms of such instruments for use in drawing ellipses or other mathematical figures.

Such instruments have heretofore taken a variety of forms including fixed size templates as well as compass-like tools for tracing figures over a wide range of sizes. The template type ellipsographs all possess the basic disadvantage of being only useful for the exact sizes for which templates are available while the latter, or compass-like ellipsographs, which is the general field into which this invention falls, have heretofore suffered from a lack of mathematical accuracy and consequently they failed to describe true projections over a range of sizes.

It is an object of this invention to provide a device of the compass-like type that will draw mathematically accurate projections of a given figure. A further object is to provide a device of the type described that will draw such figures over a wide range of sizes including every size within such range.

These and possibly other objects are attained by providing a device of the type described having a vertical first leg with a centerpoint as well as an offset holding point on its lower end, a vertically movable formed plate such as an ellipse mounted on said first leg above its lower end, means for holding such formed plate in position on said leg, a rotatable and vertically movable sleeve mounted on said first leg above said formed plate, a second leg having drawing means on its lower end and having its other end hinged to said sleeve so that said second leg moves and rotates with said sleeve while being adjustable to any degree of inclination from the longitudinal axis of said first leg, and tension means for holding the second leg against the periphery of the formed plate of the first leg, whereby when said sleeve is rotated about the first leg the second leg traces the periphery of the formed plate and the projection is transferred to the paper by the drawing means on the second leg. Size variation is attained by changing the vertical position of the formed plate of the first leg.

My ellipsograph derives its accuracy from a particular and critical arrangement of its elements. To that end it may be said that the invention is characterized in that the parts are so arranged that the longitudinal axis of the first leg passes through the center of the formed plate and intersects a straight line traced from the drawing tip of the second leg along the inner edge of such leg. The formed plate may be of any desired shape, such as an ellipse, triangle, or irregular polygons and the like.

2

When constructed in the foregoing manner the device will trace a substantially perfect projection of the shape represented by the formed plate mounted on the first leg.

5 In somewhat more detail, my invention revolves about the concept of providing a device of the type described having a vertical first leg with a center point and an offset holding point on its lower end, a formed plate having both a center hollow hub and holding means positioned on the first leg above its lower end, said plate and hub being adapted to snugly and slidably fit over said first leg to be held in place thereon by the holding means, a rotatable sleeve 10 mounted on said first leg above the formed plate, a second leg having a forked end fitting over said sleeve and pivotally mounted thereon whereby said second leg slides and rotates with said sleeve while being adjustable to any 15 degree of inclination from the longitudinal axis of the first leg, said pivot points holding the forked end of the second leg into the sleeve of the first leg being so positioned that a line drawn through said points will pass through the longitudinal axis of the first leg, spring tension means 20 holding the inner edge of the second leg against the periphery of the formed plate mounted on the first leg, and drawing means attached to the other end of the second leg and so positioned that a line drawn from the drawing means tip along the inner edge of the second leg will intersect the longitudinal axis of the first leg at the same point that the line joining the pivot points of the fork intercept said axis.

25 As this invention may be embodied in several forms without departing from the spirit or essential characteristics thereof, the present embodiment is therefore illustrative and not restrictive, since the scope of the invention is defined by the appended claim rather than by the description preceding them, all changes that fall within the metes and bounds of the claim, or equivalents of such metes and bounds, are therefore intended to be embraced by the claim.

30 40 45 In the drawings, Figure 1 is a simplified line drawing clearly depicting the critical arrangement of the elements in accordance with the concept of my invention. Figure 2 shows a preferred embodiment of the details shown in Figure 1, while Figure 3 shows a plan view of a type of formed plate adapted for use with my invention. Figure 4 is a plan view of a differently shaped plate adapted for use with this invention.

50 55 Figure 1 is a simple line drawing depicting the critical arrangement of the elements of my invention. In Figure 1 the instrument comprises a fixed vertical first leg 12 having a lower center-point 14 and an offset holding point 15 as well as

a top 13. A vertically movable formed plate 16 is mounted on leg 12. A sleeve 17 is mounted on leg 12 in such a manner that it revolves about leg 12 while being vertically slideable thereon. Attached to sleeve 17 is a movable second leg 20 having a tracing tip 21 and joining sleeve 17 at point 22, this point of juncture at 22 is such that the line A—B will always pass directly through line C—D. To this end, leg 20 may be forked at its upper end so that the forked end pivots on sleeve 17 at point 22 and its corresponding opposite point, so that lines A—B and C—D intersect with each other at a point on a line drawn between the pivot points; it is this three point intersection that provides the maximum accuracy attainable by my invention.

To insure that leg 20 will fit against the periphery of formed plate 16, there is provided a spring 23. In this way it is insured that the exact image, in mathematically correct projected enlargement, is traced by tracing point 21.

Figure 2 is a perspective of a preferred type of structure adopted to carry out the concept of my invention. In Figure 2 there is shown a compass-like drafting instrument comprising a first fixed vertical leg 212 having an inner edge 211. Mounted on leg 212 is a formed plate 216, said plate being vertically movable and capable of being fixed at any desired elevation. Leg 212 is equipped with a center point 214 and an offset holding point 215. Fixed leg 212 runs through sleeve portion 217 to terminate in holding end 213, the latter being provided with removable cap 218. Sleeve portion 217 is machined so that it fits closely upon leg 212 to minimize wobble while still permitting sleeve 217 to rotate about and slide vertically thereon.

Second leg 220 is provided hinged to sleeve portion 217 in such a manner that leg 220 rotates with sleeve 217 while being adjustable to any desired degree of inclination from the longitudinal axis of leg 212. It is desirable that the point of intersection of lines A—B and C—D also intersects a line drawn between the points at which forked end 220a pivots on sleeve 217. Leg 220 is provided with a drawing tip 221.

Leg 220 has straight inner edge 230 which is adapted to glide smoothly over the periphery of formed plate 216 thus to transcribe, via point 221, a line tracing of formed plate 216 into the same surface that supports points 214, 215 and 221. In order to insure an accurate reproduction of the periphery of plate 216, there is provided spring means 223, said spring means comprising a flat spring 223 positioned between the sides of the forked end of leg 220 and with shoulders 224 engaging the outer edges of fork 220a. The other end of spring 223 is secured to sleeve 217 by screws 225. Set screws or other conventional arrangements are provided for holding the formed plate and other removable elements in position. The formed plate is thus removable so that it may be exchanged for a different plate.

The critical constructional features of my invention are clearly depicted by lines A—B and C—D; point 222, point 221 and point 214, as well as edges 216a and 230. It is critical that straight line A—B intersects straight line C—D whenever edge 230 is in contact with edge 216a.

Figure 3 shows an ellipse-shaped formed plate 316 for use in accordance with my invention.

Figure 4 shows an alternate shape of formed plate for use with my invention.

It is to be emphasized that my invention requires that a straight line extended from the

drawing tip along the straight inner edge of the second leg will intersect the longitudinal axis of the first leg. Only in this manner will projections of varied sizes be mathematically related to each other.

Where as I have referred generally to a formed plate, it is to be understood that this invention is limited to tracing those peripheries that progress forward only and do not double back on themselves. In other words, this invention is limited to tracing peripheries that move forwardly at all times from a starting point to return to said starting point.

An inherent and important feature of this invention is the fact that it provides for varying the sizes of the traced projection over a wide range. Thus, to change the size of the tracing it is only necessary to move the formed plate up or down on the fixed leg. This feature enables the operator to trace all sizes of projections, from the largest projection when the formed plate is in its uppermost position, to the smallest projection when the formed plate is in its lowermost position on the fixed leg.

Having now described the construction and operation of my invention what I claim and desire to secure by Letters Patent is:

An improved device for drawing projections of given geometric figures, comprising a first leg with a centerpoint as well as an offset holding point on its lower end, said leg being adapted to maintain a vertical position at right angles to a surface contacted by said points, a formed plate mounted on said leg above its lower end, holding means for securing said plate at selected elevation on said leg, a rotatable and slideable sleeve mounted on said leg above the formed plate, a second leg having a forked upper end fitting over said sleeve and being pivotally mounted thereon in such a manner that a line drawn between the pivot points passes through the longitudinal axis of the first leg, said second leg having a straight lower inner edge portion adapted to contact the periphery of the formed plate, drawing means positioned on the lower end of the second leg so that the extension of a line drawn from the drawing tip along the inner edge of said leg will intersect the longitudinal axis of the first leg at the same point as that where the line through the pivot points of the forked end of said second leg intersects the longitudinal axis of the first leg, and spring tension means for holding the inner edge of the second leg against the periphery of the formed plate, said tension means comprising a flat spring positioned between the sides of the forked end of the second leg, one end of said spring having shoulders in contact with the outer edges of the forked end, and the other end of said spring being secured to the sleeve mounted on the first leg.

RAPOLAS AUKSTUOLIS.
